(57) **CLAIM**

The ornamental design for a front portion of a glove, as shown and described.

DESCRIPTION

FIG. 1 is a front perspective view of a front portion of a glove showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The dash-dot broken lines in the drawings illustrate environmental structure and form no part of the claimed design. The dash-dash broken lines illustrate portions of the front portion of a glove and form no part of the claimed design.
